UNITED STATES PATENT OFFICE.

FRITZ AHRBERG, OF BERLIN-HALENSEE, GEORG KEINATH, OF BERLIN-CHARLOTTENBURG, AND KARL SCHRADER, OF BERLIN-HALENSEE, GERMANY, ASSIGNEES TO SIEMENS & HALSKE, AKTIENGESELLSCHAFT, OF SIEMENSSTADT, NEAR BERLIN, GERMANY, A CORPORATION OF GERMANY.

HIGH-TENSION-CURRENT TRANSFORMER.

Application filed December 9, 1924, Serial No. 754,785, and in Germany December 11, 1923.

Our invention relates to improvements in high-tension current transformers. In the construction of current transformers efforts were hitherto made to employ a minimum number of ampere turns in order to keep the electro-dynamic repulsion forces within permissible limits which in the event of short-circuits may attain extraordinary high values, so that the current transformer could be considered short-circuit proof. A comparatively large quantity of iron was therefore employed in such transformers because the saturation must be kept low in spite of the desired capacity in order to avoid no-load currents which would increase the error limits to an inadmissible extent.

Our invention is based upon the recognition that by the employment of an annular iron core and an annular high-tension winding which intersect one another at right angles in known manner the electro-dynamic forces act purely centrifugally and the strength of the current transformer against such forces is equally as high as, for instance, in the single conductor current transformer which is also provided with an annular core.

According to our invention the number of the ampere turns is chosen so high that the weight of the iron is approximately equal to or less than the weight of the copper of the high-tension winding. By a high number of ampere turns a reduction of the transformation as well as of the angle error or a reduction of the cross-sectional area of the iron or a reduction in both is generally attained. In the present case particular use has been made of the latter characteristic feature. This assumes the employment of a very good insulation of the high-tension winding or primary coil from the iron core and from the low-tension winding or secondary coil. According to my invention this insulation is obtained by solid insulation materials in such a manner that these materials, running as far as possible along equi-potential coil surfaces, subdivide the arcing path of any high voltage discharge to a high degree.

In the drawing affixed to this specification and forming part thereof two embodiments of our invention are illustrated by way of example. This drawing represents in

Fig. 1 a partial elevation and partial section in the plane of the high-tension winding of one construction of the improved transformer, 55

Fig. 2 a section at right-angles to Fig. 1, with the core carrying the low-tension winding in elevation and 60

Fig. 3 a perspective view of another construction.

Similar parts are indicated by like characters in all the figures of the drawing.

Referring to Figures 1 and 2, *h* represents the terminal leads of a circular loop or coil *w* having a few windings fed with high-tension current. In other words these leads may be connected directly into the high tension line. This high tension coil *w* which forms the primary winding of the transformer, passes thru the window of an iron ring core *e* at right angles to the core plane, the window being very much larger than the transverse section of the assembled windings of the coil, so that a comparatively large intervening space remains between the coil turns and the iron core. This coil is surrounded by a paper insulation *p* consisting of wrapped layers of paper, and at the place where the iron core *e*, carrying the secondary winding *v* surrounds the primary winding at right angles to its plane the wrapping is of such thickness that it completely fills up the entire intervening space 75 of the window. The paper wrapping then 80 symmetrically gradually diminishes at both sides towards and up to the point where the supply wires *h* from the high-tension winding enter and issue, in order that the winding may be sufficiently cooled. In order to prevent a radial leakage from the less insulated portions of the winding to the iron core a saddle-like screen *s* is inserted into the remaining open space of the winding 95 which consists of a number of layers of heavy paper or similar insulating material which adapts itself substantially to the equi-potential surface portions of the coil so that an extremely great safety against leakage 100 or disruptive discharge of any kind is attained. The insulation *p* is saturated with oil or any other suitable insulating substance which is liquid when applied but becomes solid later on. The whole current transformer may also be immersed in oil. The 105

attachment of the current transformer takes place by means of angle-iron fish-plates *a* bolted to the iron core *e*. The high-tension winding *w* is secured in position upon the core *e* owing to its insulation accurately filling the core window.

The current transformer illustrated in Fig. 3 is exclusively intended for oil insulation and is therefore arranged in an oil tank not illustrated in the drawing. In this construction the direct insulation *p*¹ of the high-tension winding *w* is of uniform thickness but comparatively thin and to fill the space a number of insulating protective screens *i*, ¹⁰ *i*² of superimposed layers of paper or the like overlapping one another are provided within the core window or opening. As in the first described construction an insulating screen *s* of folded paper or the like is disposed between the outer circumference of the core *e* ¹⁵ and the high-tension winding *w*. To prevent arcing between these two screens cuff-like insulating bodies *m* of the same material as the other screens are pushed over the high-tension conductor *w* adjacent to the places where the two first mentioned screens ²⁰ meet. The arrangement and the object of all these insulating screens is here such that following as far as possible the equipotential surfaces of the coils they interrupt the insulating layers of oil at several points and thus considerably increase its total disruptive strength.

What we claim as our invention is:—

1. In a current transformer for high tension currents in combination a primary high tension coil, a secondary coil, an annular iron core having a window and carrying said secondary coil, said primary coil passing at right angles to the plane of said core through the center of the window of said annular core, the terminals of said primary winding lying within the plane but outside of said core, and a plurality of thin layers of solid insulating material enclosing said primary winding and being arranged substantially at right angles to the path of disruptive high voltage discharges, the number of said layers varying in different portions of said winding, the maximum number being located at the point where the winding passes through said window and being sufficient in number to fill up substantially the entire intervening space of the window of said core.

2. In a current transformer for high tension currents in combination a primary high tension coil, a secondary coil, an annular iron core having a window and carrying said secondary coil, said primary coil passing at right angles to the plane of said core through the center of the window of said annular core, the terminals of said primary winding lying within the plane but outside of said core, and a plurality of thin layers of solid insulating material enclosing said primary

winding and being arranged substantially at right angles to the path of disruptive high voltage discharges, the number of said layers varying in different portions of said winding, the maximum number being located at the point where the winding passes through said window and being sufficient in number to fill up substantially the entire intervening space of the window of said core, the number of layers gradually decreasing, symmetrically on both sides of the iron core plane, towards said coil terminals.

3. In a current transformer for high tension currents in combination an annular shaped primary high tension coil, a secondary coil, an annular iron core having a window and carrying said secondary coil, said primary coil passing at right angles to the plane of said core through the center of said window and insulating means for enclosing said primary winding and being arranged substantially at right angles to the path of disruptive high voltage discharges, and a separate screen of solid insulating material interposed between said primary winding and said secondary coil outside of said window.

4. In a current transformer for high tension currents in combination an annular shaped primary high tension coil, a secondary coil, an annular iron core having a window and carrying said secondary coil, said primary coil passing at right angles to the plane of said core through the center of said window and insulating means for enclosing said primary winding and being arranged substantially at right angles to the path of disruptive high voltage discharges, and a substantially annular screen of insulating material interposed between said primary winding and said secondary coil outside of said window.

5. In a current transformer for high tension currents in combination an annular primary high tension coil, a secondary coil, an annular iron core having a window and carrying said secondary coil, said annular primary coil passing at right angles to the plane of said core through the center of said window, the terminals of said annular primary coil lying within the plane but outside of said core, and insulating means for totally enclosing said annular primary coil, said insulating means being arranged substantially at right angles to the path of the disruptive high voltage discharges.

6. In a current transformer for high tension currents in combination an annular primary high tension coil, a secondary coil, an annular iron core having a window and carrying said secondary coil, said annular primary coil passing at right angles to the plane of said core through the center of said window, and the terminals of said annular primary coil lying within the plane but outside of said core, and insulating means for

- totally enclosing said annular primary coil, said insulating means being arranged substantially at right angles to the path of the disruptive high voltage discharges, said insulating means being placed so that its surface follows to a greater part of its total extension equipotential lines of the winding surface of said annular high tension coil.
7. In a current transformer for high tension currents in combination an annular primary high tension coil, a secondary coil, an annular iron core having a window and carrying said secondary coil, said annular primary coil passing at right angles to the plane of said core through the center of said window and a plurality of separate layers of solid material for totally enclosing said annular high tension coil, each of said plurality of layers being arranged substantially at right angles to the path of the disruptive high voltage discharges.
8. In a current transformer for high tension currents in combination an annular primary high tension coil, an annular iron core having a window and carrying said secondary coil, and having a cross section as will bring its weight near to that of said annular primary coil, said annular primary coil passing at right angles to the plane of said core through the center of said window and insulating means for totally enclosing said primary coil, said insulating means being arranged substantially at right angles to the path of the disruptive high voltage discharges and having a thickness within the window of said core so as to substantially fill up the intervening space in said window.
9. In a current transformer for high tension currents in combination an annular primary high tension coil, a secondary coil, an annular iron core having a window and carrying said secondary coil, and having a cross section as will bring its weight near to that of said annular primary coil, said annular primary coil passing at right angles to the plane of said core through the center of said window, and a plurality of thin layers of solid insulating material for totally enclosing said annular primary coil, the greater number of said layers following equipotential lines of said annular primary coil, said layers substantially filling up the intervening space in said window.
10. In a current transformer for high tension currents in combination an annular primary high tension coil, a secondary coil, an annular iron core having a window and carrying said secondary coil, said primary coil passing at right angles to the plane of said core through the center of said window, the terminals of said annular primary coil lying within the plane but outside of said core, and a plurality of thin layers of solid insulating material for totally enclosing said annular primary coil, the greater number of said layers following equipotential lines of said annular primary coil, and substantially filling up the intervening space in said window.

In testimony whereof we affix our signatures. 70
